W. V. BULMAN

COMBINED FLOOR DRAIN AND BACK PRESSURE WATER TRAP

Filed Dec. 14, 1925

UNITED STATES PATENT OFFICE.

WILLIAM V. BULMAN, OF PHILADELPHIA, PENNSYLVANIA.

COMBINED FLOOR-DRAIN AND BACK-PRESSURE WATER TRAP.

Application filed December 14, 1925. Serial No. 75,309.

This invention is a novel improvement in combined floor drain and back pressure traps, and the principal object of the invention is to provide a simple and efficient 5 combined floor drain and back pressure trap, in which access to the interior thereof will be readily obtainable, and which will be inexpensive to manufacture, said combined drain and trap embodying certain novel 10 features as hereinafter set forth.

I will explain the invention with reference to the accompanying drawing which illustrates one practical embodiment thereof to enable others to adopt and use the same, 15 and will summarize in the claims the novel features of construction, and the novel combinations of parts, for which protection is desired.

In said drawings:

20 Figure 1 is a longitudinal section through my novel combined drain and trap.

Fig. 2 is a top plan view thereof, partly broken away to show part of the interior construction.

25 Fig. 3 is a transverse section on the line 3—3, Fig. 1.

Fig. 4 is a detail view showing the double wall construction for receiving the back pressure flap valve plate.

30 As shown in the drawing, the combined floor drain and back pressure trap preferably comprises a casting having a vertically disposed main body portion 1 of preferably substantially circular cross section, and of 35 suitable diameter, the lower portion 1^a of body 1 contracting smoothly into a vertically disposed cylindrical neck portion 1^b, of substantially half the normal diameter of body 1, the vertical axis of neck 1^b being off-set 40 from the vertical axis of the body portion 1, as shown in Fig. 1, so that the periphery of the front portion of neck 1^b is a continuation of or is tangent to the adjacent front portion of body 1.

45 The lower end of neck 1^b terminates into an upwardly directed tubular portion 1^c, the outer end 1^d of portion 1^c being disposed substantially horizontal, with the bottom of portion 1^d disposed at about the 50 same level as the top of neck portion 1^b, whereby water or other liquid passing into the upper end of body portion 1 will be constantly retained in the neck 1^b and upwardly directed portion 1^c. End 1^d may be attached 55 in the usual manner to a soil pipe (not

shown) leading to a sewer, the drain casting being embedded in the floor of a building.

The upper end 1^e of body 1 is preferably formed into a square shape, the inside length of the sides 1^e of said square being slightly greater than the interior diameter of the body 1, thereby forming an internal shoulder 1^f at the top of body 1 adapted to receive the usual grating 2 of any desired type, whereby when the body 1 is embedded in the floor, grating 2 will be flush with the surface of said floor. Grating 2 is preferably retained in place upon shoulder 1^f by means of screws or the like, so as to be readily removable.

Above the neck 1^b, within the body 1, is an interior semi-annual flange 1^g, the plane of which flange 1^g preferably slopes downwardly and rearwardly as shown in Fig. 1, said flange extending from the front of body 1 rearwardly on both sides thereof to points somewhat beyond the inner edge of neck 1^b, the two ends of flange 1^g terminating at each side of body 1, into two spaced parallel walls 1^h, 1^k, which walls are preferably integral with flange 1^g and body 1, and as shown in Fig. 3 the walls 1^h, 1^k are preferably semi-circular, but are cut away, at their centers, as at 1^m for the reception of the flap valve plate 3 inserted between the walls 1^h, 1^k.

As shown, the parallel walls 1^h, 1^k, are disposed below and substantially at right angles to the plane of flange 1^g, whereby said walls have an upward and rearward inclination, the wall 1^k being substantially tangent to the upper inner edge of neck 1^b.

90 Flap valve plate 3 is adapted to be inserted between the walls 1^h, 1^k, and when so placed, molten lead or the like may be poured between the walls 1^h, 1^k, filling in around the edges of plate 3, whereby a tight permanent connection will be made between the walls 1^h, 1^k, and plate 3.

95 Plate 3 is provided with a top flange 3^a disposed in the plane of flange 1^g and forming a continuation of the flange 1^g and connecting the ends of said flange 1^g across the body 1. Furthermore plate 3 is provided with a central opening 3^b, having an annular shoulder 3^c, the lower edge of shoulder 3^c being disposed adjacent the upper edge of neck 1^b so that the liquid entering the top of body 1 may pass downwardly into the neck 1^b, through the opening 3^b. A flap valve 3^d normally closes opening 3^b, said valve being hinged, as at 3^e, at its upper 100 105 110

end, whereby the inclination of plate 3 will cause valve 3^a to be normally closed by gravity, preventing gas or liquid from passing upwardly from neck 1^b into body 1 past valve 3^a, but permitting liquid to readily pass from body 1 to neck 1^b.

A frame or plate 4 normally seats upon flanges 1^c and 3^a, said plate being approximately circular in shape, and provided with a gasket 4^a on its lower side adjacent the periphery thereof, to make a tight connection between the plate 4 and flanges 1^c and 3^a, plate 4 being preferably screwed down upon flange 1^c as shown. An opening 4^c is provided in the approximate center of the plate, into which is threaded a removable plug 4^d. As shown in Fig. 1, when plug 4^d is removed, the flap 3^a may be raised through opening 4^c, whereby access may be readily had to the interior of body 1.

My invention provides a simple, accessible, inexpensive, and efficient combined floor drain and back pressure trap. I do not, however, limit my invention to the exact form shown in the drawing, for obviously minor changes may be made in the details of construction within the scope of the claims.

I claim:

30. 1. A combined drain and trap, comprising a body portion having an open upper end; a trap extending from the lower end of said body, the inlet to said trap being offset from the vertical axis of the body; a flange in said body over the trap inlet; a transversely

disposed partition in the said body connecting with the ends of the flange, the upper edge of the partition lying in the plane of the face of said flange; said partition having a slot, and the edges of said slot being 40 grooved; a valve plate in said slot having its edges packed into the grooves, the upper edge of the valve plate forming a continuation of the upper edge of the partition; and a cover removably seated on the flange, partition, and plate.

2. A combined drain and trap, comprising a body having an open upper end; a trap extending from the lower end of said body, the inlet to said trap being offset from the vertical axis of the body; a perforated closure for the upper end of the body; an inclined flange in said body over the trap inlet; a transversely disposed partition in the said body connecting with the ends of the flange, the upper edge of the partition lying in the plane of the upper face of said flange, said partition having a slot open at the top, and a groove in the edge of said slot; a valve plate in said slot having its edges packed into the groove; the upper edge of the plate forming a continuation of the upper edge of the partition; a valve in said plate opening towards the trap inlet; and a cover detachably mounted on the flange and 60 the upper end of the partition and plate.

In testimony that I claim the foregoing as my own I affix my signature.

WILLIAM V. BULMAN.
